UNITED STATES PATENT OFFICE

RAYMOND F. BENNETT, OF PORTLAND, MAINE

METHOD OF LAYING UNDERWATER PIPE AND APPARATUS THEREFOR

Application filed September 21, 1929. Serial No. 394,327.

My present invention relates to the laying of pipes or mains under water and particularly to such carefully jointed pipes as are intended for continuous mains for water supply or the like.

Such pipes or mains are usually laid in a trench dredged at sea bottom and frequently at considerable depth. The great problem is to get the pipe sections carefully jointed together above water and deliver them at the bottom as a continuous main with certain flexibility without over-straining any of the joints.

It has been customary heretofore to assemble the pipe sections on a lighter or scow and to slide the pipe so connected down an inclined chute from the lighter, but this has involved much difficulty on account of the movements of the lighter and chute on account of the waves and the variations of depth due to tides, and changes in elevation of the bottom, and on account of changes in slope of the bottom.

Furthermore, where the pipe is to be laid in a trench much difficulty has been experienced in holding alignment with it and it is of course important that the pipe be laid accurately as well as steadily.

My invention contemplates a different basis of operation, first, in that it isolates the assembly and delivery from a floating to a fixed support. Secondly, it conceives of a bottom level basis not only for pipe delivery but for trench digging. In the third place, it gains a basis of accuracy heretofore impossible at different depths and varying tides.

As illustrative of my invention I have shown in the accompanying drawings of apparatus and by diagram an installation characteristic of the problem and of individual importance in detail.

In the drawings, in which like reference characters are employed to indicate the parts discussed in the specification,

Fig. 1 is a somewhat diagrammatic side elevation of equipment in operation.

Fig. 2 is a diagrammatic plan view.

Fig. 3 is an end elevation, and

Fig. 4 is a detail of the pipe laying.

As indicated in the drawings, the problem

involved is that of assembling the pipe sections of a continuous main and usually in laying such sections in a trench indicated generally at T.

In accordance with my invention the operation may be carried on in a substantially continuous manner, the trench being dug by any suitable dredging apparatus as indicated at D, and the pipe being assembled on a movable laying apparatus supported on the bottom and preferably spanning the trench along which it is progressed as the pipe is laid.

While such apparatus is capable of various structural embodiments, I have shown and will describe a simple and inexpensive equipment which I have found well adapted to meet difficult conditions and which well illustrates means for carrying out my concept of operation in accordance with my invention.

As shown in the drawings I preferably provide a pair of spaced bottom supports or shoes S. These are set at such distance apart as to span the trench and afford a stable base for the super-structure on which the pipe sections are to be assembled and from which they are to be laid as a continuous main. The bottom members or runners S which in the form shown are double timbers support front risers 4 and rear risers 5. The front risers are cross braced as at 6 and 7 and the rear risers similarly cross timbered as at 9 and 10. The side pairs 4 and 5 are braced diagonally as at 8. Centrally of this structure and rearwardly thereof I extend a brace 12 sloped downwardly to below the level of the bottom members S. This constitutes a support for the chute 1 down which the assembled pipe sections are delivered after assembly. The chute 1 comprises a curved section 1¹ which is curved on the arc of a circle on a radius just sufficient to give the pipe the proper degree of flexation after assembly. It is important that the pipe be thus initially flexed after assembly in order that there may be sufficient freedom in the joint to allow the main to accommodate itself to the bottom. At its upper end the chute 1 is disposed as tangent to this curved section and constitutes the assem-

bly area of the chute. This tangential section, if space is limited, or if it is desired to make the apparatus as small as possible, may be depressed at its upper end from the point 5 of tangency into a position parallel to a chord of the curved portion extending from this point of tangency one pipe's length. I provide platform members 18-18 disposed on each side of this tangential portion of the 10 chute and these platform members are cleated so as to provide a convenient assembly station for the men engaged in jointing up the pipe sections.

The chute 1 is supported adjacent its lower 15 end by the chute brace 12 before described. I provide suitable braces as indicated at 14, 15, 16 and 17 so that the lower end of the chute which in practice extends a considerable distance beyond the tower section is 20 steadily braced. This lower end is continued down to the intended bottom level of the trench in which the pipe is to be laid. As heretofore suggested, one of the difficulties 25 has been to dredge a trench under water with reasonable regularity of depth. It has been difficult to gage the proper dredging depth on account of variation in the bottom and variations in tide. By providing gage markings 30 G on the superstructure of the pipe laying apparatus, I am able on account of its bottom supported nature to provide for a very accurate dredging for the depth of trench regardless of the depth of water in which the dredging is being done. By observing the 35 gage markings the dredge operator is able to tell exactly how much allowance to make in order to provide the trench of the desired depth so that the lower end of the chute 1 will trail at the bottom of the trench and 40 thus deliver the pipe with a minimum of disturbance of the joints.

The structure shown is usually weighted by convenient ballast W so as to hold it steady and against any flotation tendency. 45 As the pipe P is coupled on the straight portion of the chute 1 I find it important to secure an initial flexation of the joints as the pipe is slid down into the curved section of the chute. For this purpose I provide a flexible cable attached at 2¹ to one of the supports 5 adjacent its base, this being passed over the pipe in chute 1 and through a block 3 on the opposite side. The cable 2 is conveniently provided with a loop 2² which when 50 the cable is not in use is simply hooked over some portion of the assembly station. When the pipe is being slid down the joints are flexed by putting tension on the cable, as for example, by hooking the whip of the lighter 55 indicated at L on to the loop and thus obtaining power to draw the pipe sections firmly against the chute. The lighter L may be located in any convenient manner. As shown, it is laid alongside of the pipe assembly 60 station so that pipe sections can be de-

livered as desired. When it is desired to lay a section of assembled pipes, the whole pipe delivery apparatus is slightly lifted or eased from the bottom by the lighter derrick and the lighter warped forward by its line H. 70 This advances the chute along the trench and at the same time permits the assembled pipe sections to slide down the chute delivering those adjacent its lower end into the trench where they soon become covered by the natural movements of the water in shifting the dredged material of the bottom or the trench may be backfilled by other means. In order to force the pipe into proper position in the curved portion of the chute I provide a roller 75 19 supported on brackets 20 on each side of the chute under which the pipe passes as it is fed down the chuteway as an alternative device to the cable 2.

The operation before described provides for what is really a continuous operation even though it be carried out somewhat intermittently. It is continuous in the sense that the dredging can be carried on as rapidly as pipe sections can be assembled and the laying apparatus moved ahead to follow the trench. Such a method is very economical and very efficient. The mains can be laid at any stage 80 of the tide and in almost any weather, and without danger of breakage. The apparatus 85 and equipment indicated may of course be varied and obviously any convenient type of lighter or dredge may be used.

What I therefore claim and desire to secure by Letters Patent is:

1. A device for the use in laying sectional mains in a preformed underwater trench, comprising a pair of tower supports secured in lateral spaced relation to rest on the bed of the water body on either side of the trench, respectively, a tower structure built upon and rising from said supports, a chute supporting brace secured at its forward end to said tower structure and extending rearwardly therefrom beyond the rear ends of said tower supports and at a downward inclination to rest at its rear end on the trench bottom, a chute supporting framework erected on said brace, and a downwardly and rearwardly directed chute mounted at its forward end on said tower and at its rear end on said framework and said brace for guiding pipe sections assembled on the front upper end thereof downwardly and into the trench when the device is moved forward.

2. A device as set forth in claim 1 in which the chute is in the form of a trough straight at its upper end and curved intermediate its ends, an in which a roller is provided for co-operation wth the curved portion of the trough to cause adjacent pipe sections to be moved from a position in axial alinement to an axially disaligned position during their movement down said trough.

3. In a device as set forth in claim 1 in

which the chute is curved intermediate its ends and means is provided for cooperation with the curved portion of the chute to cause adjacent sections of the pipe to be moved from a position in axial alinement to an axially disaligned position during their movement down said chute.

4. A device for use in laying sectional mains under water, comprising a pair of tower supports secured in lateral spaced relation to rest on the bed of the water body on either side of the line of work, respectively, a tower structure built upon and rising from said supports, a chute supporting brace secured at its forward end to said tower structure and extending rearwardly therefrom beyond the rear ends of said tower supports and at a downward inclination to rest at its rear end on said bed, a chute supporting framework erected on said brace, and a downwardly and rearwardly directed chute mounted at its forward end on said tower and at its rear end on said framework and said brace for guiding the pipe sections assembled on the front upper end thereof downwardly and into line when the device is moved forward.

In testimony whereof I affix my signature.
RAYMOND F. BENNETT.
